Specification for Design.

Patented Jan. 9, 1917.

Application filed May 3, 1916. Serial No. 95,278. Term of patent 14 years.

To all whom it may concern:

Be it known that I, ROLLIE B. FAGEOL, a citizen of the United States, residing in Oakland, county of Alameda, State of California, have invented a new, original, and ornamental Design for a Vehicle, of which the following is a specification, reference being had to the accompanying drawing, forming part thereof, wherein the figure is a view in side elevation of a vehicle, showing my new design.

I claim:—

The ornamental design for a vehicle, as shown.

In witness whereof I have signed my name to this specification in the presence of two witnesses.

ROLLIE B. FAGEOL.
